CLOTH FOLDING MACHINE

Richard G. Crowe, Normandy, Mo.

Application October 17, 1947, Serial No. 780,493

4 Claims. (Cl. 270—40)

1

This invention relates to folding machines for cloth and the like, and more particularly to a machine for folding heavy goods, such as canvas or waterproofed fabric, whereby the goods is prepared for cutting to required lengths.

A main object of the invention is to provide a novel and improved machine for folding web material such as cloth to reduced width prior to cutting the material to desired lengths, as required by subsequent operations, said machine being very simple in construction, easy to operate, and providing a great saving in time and labor in the handling of the material.

A further object of the invention is to provide an improved machine for handling heavy cloth, such as canvas or waterproofed fabric, as well as lighter textile materials, said machine folding the cloth to a width convenient to handle for cutting the cloth to a desired length, the machine being inexpensive to construct, readily adjustable to change the size of the folds, and reliable in operation.

Further objects and advantages of the invention will become apparent from the following description and claims, and from the accompanying drawings, wherein:

Figure 1 is a side elevational view of a machine for folding web material to desired width constructed in accordance with the present invention.

Figure 2 is a top plan view of the machine of Figure 1 but showing no cloth in the slat portion of the machine.

Figure 3 is a vertical transverse cross-sectional view, enlarged in scale, taken on line 3—3 of Figure 1.

Figure 4 is an enlarged longitudinal detail cross-sectional view taken on line 4—4 of Figure 2.

Figure 5 is an enlarged vertical transverse detail view taken on line 5—5 of Figure 1.

Figure 6 is a top plan view similar to Figure 2, but showing the cloth passing entirely through the machine, whereby it is folded to reduced width.

Figure 7 is an enlarged cross-sectional detail view taken on line 7—7 of Figure 2.

Figure 8 is a transverse cross-sectional detail view taken on line 8—8 of Figure 2, showing the pleating bars of the machine in end elevation.

Referring to the drawings, 11 designates a generally rectangular table having vertical supporting legs 12 at its respective corners. Journaled in bearing brackets 13 secured to the legs 12 at one end of the table is a transverse shaft

2

14 on which is wound the roll of cloth 15 which is to be folded to reduced width prior to cutting. Secured to the table at said end are pairs of upstanding brackets 16, 16, 17, 17, 18, 18, and 19, 19, 5 in which are journaled the respective transverse free rollers 20, 21, 22 and 23, around which the cloth from roll 15 is threaded, the cloth passing under the forward roller 23 adjacent the table surface, as shown in Figure 1.

10 Secured to the table forwardly adjacent roller 23 is a transverse plate member 24 and projecting vertically upwardly from each end portion of said plate member is a post member 25. Secured to the top ends of the post members 25 is a trans- 15 verse plate member 26. Secured to the table forwardly of plate member 24 is a transverse plate member 27 and projecting upwardly from each end portion of plate member 27 are vertical post members 28, 28. Secured to the top ends of the 20 post members 28, 28 is a transverse plate member 29.

Secured to the transverse bottom plate members 24 and 27 between the respective end posts of said plate members are longitudinally-extending vertical slats 30, uniformly spaced in a transverse direction and substantially greater in height than half the height of the end posts, but substantially less than the full height of said end posts. The top edges of the slats 30 are inclined 30 downwardly and rearwardly at their rear ends, as shown at 31.

Adjustably secured to the transverse top plate members 26 and 29 and depending therefrom are longitudinally-extending vertical slats 32 which 35 are spaced so as to lie in longitudinal vertical planes midway between the planes of the bottom slats 30. The height of the slats 32 is substantially the same as that of the slats 30 and the rear bottom edges of the slats 32 are inclined upwardly, as shown at 33.

40 The rear end portions of the slats 32 are adjustably fastened to plate member 26 by bolts 34 threaded through plate elements 34' secured to plate member 26. The bolts 34 are locked in adjusted positions by wing nuts 35 which are tightened on the bolts 34 so as to bear on the plate elements 34'.

45 The forward end portions of slats 32 are adjustably fastened to plate member 29 by longer bolts 37 threaded through plate elements 37' secured to plate member 29. The bolts 37 are locked in adjusted positions by wing nuts 38 which are tightened on the bolts 37 so as to bear on the plate elements 37'.

50 As shown in Figure 4, the bolts 34 and 37 are adjusted to provide a certain amount of vertical play for the rear and forward

end portions of the slats 32 so that said slats are free to move vertically within predetermined limits during the operation of the machine.

Secured on the forward portion of the table 11 is a transverse frame or yoke 40 in which are journaled a pair of vertical rollers 41, 41 similar to conventional wringer rollers, said rollers being maintained in squeezing engagement with each other in the same manner as the wringer rollers of a conventional washing machine. A conventional release lever 42 is provided on the wringer roller unit 40, whereby the clamping pressure on the rollers 41, 41 may be released and the rollers may be separated if desired. The rollers are coupled together for simultaneous rotation in opposite directions by gears 43, 43 carried on their shafts, and the shaft of one of the rollers carries a bevel gear 44 at its lower end. Said shaft depends through an opening 45 formed in the table top. Secured beneath the table top is a bearing bracket 46 in which is journaled a transverse shaft 47 carrying a bevel gear 48 which meshes with bevel gear 44. Said shaft also carries a pulley 49 which is coupled by a belt 50 to the shaft of a motor 51 mounted beneath the table.

The wringer rollers 41, 41 are substantially symmetrically spaced with respect to the longitudinal vertical central plane of the table and the slat assemblies.

In operation, cloth from roll 15 is passed through the feed rollers 20, 21, 22 and 23 in the manner illustrated in Figure 1, and is received between the inclined rear edge portions 31 and 33 of the respective slats 20 and 32. The cloth is first pulled manually through the slats, whereby it is longitudinally pleated, and the pleated cloth is fed between the wringer rollers 41, 41. The wringer rollers grip the pleated cloth, and when the motor 51 is energized, provide the required tension to pull the cloth through the pleating slats 32 without further attention on the part of the operator.

The folded cloth which leaves the wringer rollers 41, 41 is fed to a cutting table, not shown, where it is cut to desired lengths, as required by subsequent operations.

The pleating action is obtained by the weight of the floating upper slats 32 acting on the cloth between adjacent stationary slats 30, as well as by the fact that the slats are each substantially greater than half the height of the respective supporting posts 28, 28 and 25, 25. The folds defined by the pleats are completed by the transverse compression exerted thereon by the wringer rollers 41, 41 as the converged pleats are drawn through said rollers, as shown in Figure 6. The resultant folded cloth is thereby reduced to a width convenient to handle and to cut to desired length.

The height of the slats and the number of slats employed may be varied in accordance with the width of the material to be folded.

While a specific embodiment of a machine for folding cloth or other web material has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A machine for forming longitudinal folds in a web fed longitudinally therethrough, said machine comprising a horizontally elongated support, a folding unit on said support compris-

ing a lower set of longitudinally arranged parallelly spaced slats secured to rise from said support, an upper set of longitudinally arranged parallelly spaced slats supported to depend with their lower edges between and below the upper edges of the slats of the lower set, substantial portions of the upper edges of the lower slats and of the lower edges of the upper slats being rearwardly tapered to the rearward ends of the slats, and a pair of opposed vertical pressing rollers positioned on said support in forwardly spaced relation to said folding unit for pressing the folds formed between the upper and lower slats of said folding unit as the unfolded web is fed forwardly through said folding unit and the folded portion of the web emerging forwardly from said unit is fed between said pressing rollers, means supporting said upper slats comprising transverse elements supported above said support and extending transversely across the opposite ends of said lower set of slats, and vertically adjustable elements on each of said transverse elements secured to longitudinally spaced portions of said upper slats.

2. A machine for forming longitudinal folds in a web fed longitudinally therethrough, said machine comprising a horizontally elongated support, a folding unit on said support comprising a lower set of longitudinally arranged parallelly spaced slats secured to rise from said support, an upper set of longitudinally arranged parallelly spaced slats supported to depend with their lower edges between and below the upper edges of the slats of the lower set, substantial portions of the upper edges of the lower slats and of the lower edges of the upper slats being rearwardly tapered to the rearward ends of the slats, and a pair of opposed vertical pressing rollers positioned on said support in forwardly spaced relation to said folding unit for pressing the folds formed between the upper and lower slats of said folding unit as the unfolded web is fed forwardly through said folding unit and the folded portion of the web emerging forwardly from said unit is fed between said pressing rollers, means supporting said upper slats comprising transverse elements supported above said support and extending transversely across the opposite ends of said lower set of slats, and vertically adjustable elements on each of said transverse elements secured to longitudinally spaced portions of said upper slats, said vertically adjustable elements being adjustable to vary the penetration of said upper slats into the spaces between related pairs of said lower slats and thereby vary the width of folds formed in the web.

3. A machine for forming longitudinal folds in a web fed longitudinally therethrough, said machine comprising a horizontally elongated support, a folding unit on said support comprising a lower set of longitudinally arranged parallelly spaced slats secured to rise from said support, an upper set of longitudinally arranged parallelly spaced slats supported to depend with their lower edges between and below the upper edges of the slats of the lower set, substantial portions of the upper edges of the lower slats and of the lower edges of the upper slats being rearwardly tapered to the rearward ends of the slats, and a pair of opposed vertical pressing rollers positioned on said support in forwardly spaced relation to said folding unit for pressing the folds formed between the upper and lower slats of said folding unit as the unfolded web

is fed forwardly through said folding unit and the folded portion of the web emerging forwardly from said unit is fed between said pressing rollers, means supporting said upper slats comprising transverse elements supported above said support and extending transversely across the opposite ends of said lower set of slats, and vertically adjustable elements on each of said transverse elements secured to longitudinally spaced portions of said upper slats, said vertically adjustable elements on each of said transverse elements being individually adjustable to vary the inclination of the lower edges of said upper slats relative to said support, and to vary the depth of penetration of the upper slats into the spaces between related pairs of said lower slats, whereby to vary the width of individual folds formed by passage of said web forwardly through said folding unit.

4. A machine for forming longitudinal folds in a web fed longitudinally therethrough, said machine comprising a horizontally elongated support, a folding unit on said support comprising a lower set of longitudinally arranged parallelly spaced slats secured to rise from said support, an upper set of longitudinally arranged parallelly spaced slats supported to depend with their lower edges between and below the upper edges of the slats of the lower set, substantial portions of the upper edges of the lower slats and of the lower edges of the upper slats being rearwardly tapered to the rearward ends of the slats, and a pair of opposed vertical pressing rollers positioned on said support in forwardly spaced relation to said folding unit for pressing the folds formed between the upper and lower

slats of said folding unit as the unfolded web is fed forwardly through said folding unit and the folded portion of the web emerging forwardly from said unit is fed between said pressing rollers, means supporting said upper slats comprising transverse elements supported above said support and extending transversely across the opposite ends of said lower set of slats, and vertically adjustable elements on each of said transverse elements secured to longitudinally spaced portions of said upper slats, said vertically adjustable elements on each of said transverse elements being individually adjustable to vary the inclination of the lower edges of said upper slats relative to said support, and to vary the depth of penetration of the upper slats into the spaces between related pairs of said lower slats, whereby to vary the width of individual folds formed by passage of said web forwardly through said folding unit, said vertical adjustable elements having lost motion connection with said upper slats providing for limited free vertical motion of said upper slats during the passage of the web through said folding unit.
